UNITED STATES PATENT OFFICE.

CHARLES S. W. BARWELL, OF LONDON, ENGLAND.

DESIGN FOR A BOTTLE.

56,733.

Specification for Design.

Patented Dec. 14, 1920.

Application filed February 5, 1920. Serial No. 356,410. Term of patent 7 years.

To all whom it may concern:

Be it known that I, CHARLES SEDLEY WILLIAM BARWELL, a subject of the King of Great Britain, residing at 283 Regent street, London, England, have invented a new, original, and ornamental Design for a Bottle, of which the following is a specification, reference being had to the accompanying drawing, forming part thereof.

The figure is a view in side elevation showing my new design.

I claim:

The ornamental design for a bottle as shown.

CHAS. S. W. BARWELL.
